Primary Examiner—Louis S. Zarfas*Attorney, Agent, or Firm*—Cohen, Pontani, Lieberman, Pavane[57] **CLAIM**

The ornamental design for a carrying case for a toothbrush, as shown and described.

DESCRIPTION

FIG. 1 is a rear perspective view of a carrying case for a toothbrush showing my new design;

FIG. 2 is a front elevational view thereof;

FIG. 3 is a bottom plan view thereof;

FIG. 4 is a top plan view thereof;

FIG. 5 is a perspective view thereof with the carrying case shown in the open position; and,

FIG. 6 is a right side elevational view thereof.

The broken line showing of a toothbrush in FIG. 5 is for illustrative purposes only and forms no part of the claimed design.

FIG. 1

FIG. 2

FIG. 3

FIG. 4

FIG. 5

FIG. 6
